UNITED STATES PATENT OFFICE.

WALDO A. HOWLAND, OF ADAMS, MASSACHUSETTS.

AUTOMATIC VACUUM BREAKER.

Application filed April 10, 1920. Serial No. 372,818.

To all whom it may concern:

Be it known that I, WALDO A. HOWLAND, a citizen of the United States, residing at Adams, in the county of Berkshire and State 5 of Massachusetts, have invented certain new and useful Improvements in Automatic Vacuum Breakers, of which the following is a specification, reference being had to the accompanying drawings.

10 This invention relates to means for breaking the vacuum in steam plants, and particularly to means for operating a vacuum valve in the steam plant to insure safety against accident by water rushing into a cylinder 15 under certain contingencies, which would wreck the power plant.

The general object of this invention is to provide a positive, quick acting, automatic vacuum breaker, and more particularly to 20 provide a vacuum breaking valve normally held to its seat, and provide means operated by the rise of a float in a chamber or receptacle connected to the condenser or exhaust pipe of the water feed whereby this valve 25 may be lifted from its seat to thereby break the vacuum.

A further object is to provide a construction of this character in which the vacuum valve is connected to a vertically movable 30 piston or equivalent device, this piston being normally lowered to lower and hold the vacuum valve to its seat, but being raised by the inlet of water under pressure beneath the piston, this inlet of water beneath the piston 35 being controlled by a quickly operating valve, in turn controlled by a float, piston or equivalent device actuated by an undue rise of water in a chamber connected to a condenser or to the exhaust pipe or in like position.

40 Other objects will appear in the course of the following description.

My invention is illustrated in the accompanying drawings, wherein:—

45 Figure 1 is a side elevation of an apparatus constructed in accordance with my invention, parts being shown in section;

Figures 2 and 3 are vertical longitudinal sections through the valve casing of the apparatus;

Figure 4 is a detailed sectional view through the water cylinder;

Figure 5 is an elevation of a condenser and exhaust pipe with my invention applied thereto.

Referring to the drawings, 10 designates

a chamber, illustrated as cylindrical in form, and having a head 11 at its lower end and a head 12 at its upper end having screw-threaded engagement with the cylinder. 60 This head 11 is provided with an inlet opening 13 in its middle which is connected to the condenser or to the exhaust pipe of the engine. The head 12 has a stuffing box 14 attached to its middle, and extending through 65 this stuffing box is a float rod 15 which, at its lower end, engages with a float 17. This float 17 is preferably an open bottom float, though I do not wish to be limited to that, that is it is closed on its top and at its sides 70 but open at its bottom so that the float cannot at any time become water logged. This float 17 at its upper end is provided with a boss 18 to which the float rod is operatively connected. 75

Disposed above the cylinder or chamber 10 is a valve casing 19 containing a controlling or motor valve. I have illustrated a certain form of valve, such as is described in Patent #924,559 of June 8, 1909, but I do not wish 80 to be limited to this valve. This valve casing has a longitudinally extending chamber or bore of uniform diameter and from the middle of the valve chamber extends the outlet port 20. Disposed below the outlet port 85 20 and illustrated as being diametrically opposite to the port 20 is an inlet port 21, and in line with this inlet port but above the port 20 is the discharge port 22. Disposed between the inlet port 21 and the outlet 20 is 90 a bushing 23 having a central passage for the valve stem. Below this bushing 23 and below the port 21 is a bushing 24 also having a central opening for the valve stem. Between the port 20 and the port 22 is a bushing 25 having a central opening. Extending vertically through the valve casing is the stem 26 which extends through an oil receptacle 27 formed in the upper portion of the casing and above a liquid-tight bushing 28 100 in the upper portion of the casing. The stem 26 is reduced in diameter, at 29. The stem then extends downward for a certain portion of its length and is uniform in cross section for this part of its length, as at 30, and below 105 this part 30 is preferably square in cross section, as at 31, so that the stem is guided within the bores of the bushings 23 and 24 but permits the passage of liquid through the openings in these bushings when the stem is 110 shifted in a certain direction. The port 21 is connected by means of a pipe 32 with any

source of water under pressure, as for instance, it might be connected to the city main or to any other source of water. The port 20 is connected by a pipe line 33 to the vacuum 5 valve operating chamber, as will be later stated, and the port 22 is connected by a pipe 34 to any suitable point of discharge. The stem 26 is carried by a loop-shaped yoke 35 which extends downward on each side of the 10 valve casing 19 and at its lower end is connected to the stem 15.

It will be obvious now that when the float 17 rises, the valve stem 26 which constitutes the valve itself, is lifted and this 15 lifting action shifts the valve from the position shown in Figure 3 to that shown in Figure 2, thus connecting the ports 21 and 20. When the valve stem is lowered, communication between these ports is cut off 20 and any leakage past the valve is carried away through the waste or discharge port 22 and pipe 34. As illustrated, a bracket 36 is mounted upon the cover or upper head 12 of the chamber 10 and engages the pipe 25 line 33 adjacent the valve casing 19 and supports this valve casing in position against movement.

The vacuum breaker valve is designated generally 37 and normally seats upon a 30 seat formed on the upper face of a body 38 which is shown as screw-threaded and engaged with an exhaust pipe 39 leading from the engine to the condenser. I do not wish to be limited to any particular construction 35 for the valve 37 and the valve seat or body 38, nor to the use of this valve in the exhaust pipe.

For the purpose of raising or lowering this valve, I provide a water cylinder or 40 chamber 40 supported by legs 41 extending from the pipe, chamber or receptacle 39 and securely bolted thereto and having an inlet port 42 to which the pipe line 33 is connected. This chamber 40 is closed by a 45 head 43 having an upward extension 44 in which is disposed a coiled spring 45 and having an opening or vent 40a. Extending downward through this extension 44 is a stem 46 constituting a piston rod and carrying upon it a piston or equivalent element 47. This may be in the form of an inverted "bucket" valve or may be of any other suitable form and is provided with rings or water grooves on its circumference or is otherwise suitably packed so that when the valve 50 shifts to admit water through the line 33 into the interior of the cylinder 40, this piston 47 will rise. The upper end of the piston rod 46 is connected to a yoke 48 which extends downward and is formed with two spaced ears 49 to receive between them a lug 50 formed on the upper end of the breaker valve, this lug being pivoted to these ears by a yoke pin 51. The spring 55 within the extension 44 bears downward on

the piston head 47 so that the valve 37 is urged downward by the spring and by the weight of the piston, piston rod, yoke, and the valve itself.

Extending from the chamber 10 in which 70 is disposed the float 17 is an equalizer pipe 53. This equalizer pipe is connected to the condenser A to which the inlet 13 is connected but is two or three sizes smaller than the inlet. For instance, if the inlet opening is $1\frac{3}{4}$ " in diameter, the equalizer has an 75 interior diameter of $\frac{3}{4}$ ".

The operation of this mechanism is as follows: If for any reason the water in the condenser or exhaust pipe to feed water heater for instance, begins to rise above its normal height and thus is liable to be drawn into the cylinders of the engine and it is necessary, therefore, to break the vacuum in the exhaust pipe, then this water enters the 80 chamber 10, and if the water therein rises from $1\frac{1}{2}$ to 2", for instance, the float 17 rises and the motor valve formed by the stem 26 opens very quickly to its full port opening. This allows the water under pressure or 85 head to flow through pipe 32 and the valve casing through pipe line 33 to the valve lifting cylinder 40 and this quickly raises the piston 47 therein $\frac{3}{8}$ ", for a 2" valve, and this will lift the vacuum breaker valve $\frac{3}{8}$ " 90 off its seat. This valve remains thus suspended until the level of the water in the receptacle to which the chamber 10 is connected lower or returns to its normal height. This return of the water causes the closing 95 of the valve stem 26 and the cutting off of communication between the source of water and the water cylinder, whereupon the weight of the piston, piston rod, yoke, and valve, together with the spring 45, will cause the closing of the breaker valve, the water flowing backward through the pipe 33 and being discharged through the discharge pipe or port 22. Any leakage of water past the piston 47 is taken care of by 100 one or more leakage vents 54 in the upper part of the cylinder.

While I have illustrated a particular form of controlling valve, namely that illustrated in Patent #924,559, yet I do not wish to be limited to any particular form of valve, as I may use, for instance, the form of valve or motor made by the Spencer Regulator Company, the Locke Regulator Company (covered by the patent above referred to) or a 115 rocking valve, that is a Corliss valve. Neither do I wish to be limited to any particular form of float 17, but preferably I use an open bottom float so that the float cannot become water logged, as might be 120 the case were the float a sealed or closed float, that is a hollow casing filled with air. As a float in chamber 10, I may use an inverted bucket float, an open bucket float, or a sealed float or a piston. In other words, 125 130

I may use as a motor for the valve 26 any device which will be shifted by the rising of water within the chamber 10. Neither do I wish to be limited to any particular form 5 or the piston 47, as this may be in the form of an inverted bucket or an open bucket or a plain piston.

While I have heretofore referred to the inlet pipe 32 as being connected to a source 10 of water under pressure, as for instance, a city main, yet this water may be had from a steam condenser coil, or if the boiler feed pump uses cold water, it may be taken from that as a source. There should be approxi- 15 mately 30 pounds of pressure per square inch on the motor valve at all times when power is used.

The chamber 10 is connected to the condenser A just above the normal water level 20 by the pipe 13. The equalizer pipe 53 extends into the condenser about 14" above the connection 13. It is, of course, understood that the condenser and its pump are always placed as far below the engine cyl- 25 inders as possible. Now it will be understood that if the water in the condenser rises above a certain amount, due to there being a more intense vacuum in the cylinder than at the condenser, which condition may be 30 caused by the stoppage of the air pump or circulating pump before the engine is stopped, or because the engine has not given free exhaust to the air, then as soon as the rising water seals the inlet pipe 13 to the 35 chamber 10, the vacuum existing higher up in the condenser at once begins to assist in causing the water to enter the chamber 10 below the float or piston 17 and, of course, assists in the quick action of the motor valve 40 stem 26. This is very important, as it removes any possibility of the float or piston not functioning properly. Of course, the rise of water in the chamber 10 and the consequent lifting of the controlling valve causes the 45 lifting of the vacuum breaking valve 37 which is on the other side of the incoming water moving toward the cylinder, and when the valve 37 lifts off its seat, it admits air to the exhaust pipe, which breaks the vacuum, 50 and the water again seeks a lower level.

It will be noted that the valve 37 is connected to the piston 47 by the yoke 48 so that the piston is connected to the yoke by the upwardly extending stem 46 instead of 55 a downwardly extending stem extending through the bottom of cylinder 40. This is done to obviate the necessity of a stuffing box on the under side, as the water thrust is all upward and any leakage of water is 60 thrown out through the vent opening 40^a in the upper end of the cylinder. If stuffing boxes are used, engineers would be very liable to stop any water drip or leakage through the stuffing box and would tighten 65 up the stuffing box, thus impeding the free

movement of the parts. What is true of the construction of the cylinder 40 is equally true of the valve casing 19. This is not formed with a stuffing box at its upper end and thus friction is reduced, it being almost 70 a necessity in constructions of this character that friction should be reduced to a minimum. Of course, the quickness of operation of the mechanism, that is the quickness of response of the vacuum valve, depends to a 75 certain extent upon how closely the cylinder 40 is located to the chamber 10, and the closer these two instrumentalities are, the quicker the vacuum valve will respond.

One of the particular advantages of this 80 construction, aside from those previously pointed out, is that all of the mechanism may be disposed in a very small space, or the two elements of the mechanism, namely the controlling valve mechanism with its cham- 85 ber 10 and float and the vacuum valve operating mechanism may be disposed a considerable distance from each other and connected by the pipe 33, thus accommodating the mechanism to any particular circum- 90 stance of operation.

I claim:—

1. The combination with an element having a valve seat and a normally closed vacuum valve therein, of a cylinder disposed 95 above the vacuum valve, a piston operating therein and having an upwardly extending stem extending through the head of the cylinder, a yoke carried by the upper end of the stem and extending downward around 100 the cylinder and at its lower end operatively connected to the vacuum valve, a controlling valve casing communicating with a source of liquid under pressure and having a pipe connection extending to the lower 105 end of the cylinder beneath the piston there- 110 of, a float chamber, a float therein, a valve disposed within the controlling valve casing and operatively connected to the float, said float when lowered causing the valve to cut off communication between the source of liquid and the cylinder and when raised shifting the valve to open communication between the liquid and the cylinder.

2. The combination with an element having a valve seat and a normally closed vacuum valve therein, of a cylinder disposed above the valve, a piston operating within the cylinder and having a stem extending out therefrom, a yoke operatively connecting the stem to the valve, means normally holding the valve closed and the piston depressed, and a controlling valve casing connected to a source of fluid under pressure and to said cylinder beneath the piston 125 thereof, a valve therein in one position cutting off communication between the source of fluid and said cylinder, a chamber having communication with a source of liquid, and a member disposed in said chamber and 130

raised by the increase of level of liquid therein, said member being operatively connected to the controlling valve to shift it to an open position when the member is raised.

3. The combination with an element having a valve seat and a normally closed vacuum valve therein, of a cylinder mounted above the vacuum valve, a piston operating therein and having an upwardly extending stem extending through the head of the cylinder, a spring urging said piston downward, a yoke carried by the upper end of the stem and extending downward around the cylinder and at its lower end operatively connected to the vacuum valve, a controlling valve casing communicating with a source of liquid under pressure and having a pipe connection extending to the lower end of the cylinder beneath the piston thereof, a float chamber, a float therein, a valve disposed within the controlling valve casing and operatively connected to the float, said float when lowered causing the valve to cut off communication between the source of liquid and the cylinder and when raised shifting the valve to open communication between the liquid and the cylinder.

4. The combination with an element having a valve seat and a normally closed vacuum valve therein, of a cylinder mounted above the vacuum valve, a piston operating therein and having an upwardly extending stem extending through the head of the cylinder, a spring urging said piston downward, a yoke carried by the upper end of the stem and extending downward around the cylinder and at its lower end operatively connected to the vacuum valve, a controlling valve casing communicating with a source of liquid under pressure and having a pipe connection extending to the lower end of the cylinder beneath the piston thereof, a float chamber, a float therein, a valve disposed within the controlling valve casing and operatively connected to the float, said float when lowered causing the valve to cut off communication between the source of liquid and the cylinder and when raised shifting the valve to open communication between the liquid and the cylinder, said controlling valve casing having a discharge outlet and said valve when lowered establishing communication between said discharge outlet and pipe connection to the cylinder.

5. The combination with the exhaust pipe of an engine, and a condenser, of a valve seat formed in the exhaust pipe, a normally closed vacuum valve operating therewith, a motor operatively connected to the vacuum

valve to raise it when the motor is actuated, means for actuating the motor when the condenser is filling with water including a controlling valve, a chamber having a duct at its lower end connected to the lower portion of the condenser, said chamber at its upped end having a relatively smaller duct connected to the upper portion of the condenser, both of said ducts being of a diameter small relative to the diameter of said chamber, and a float operating within said chamber and having a diameter nearly equal to that of the chamber, said float being directly connected to the controlling valve whereby to cause the actuation of the controlling valve, the motor, and the lifting of the vacuum valve upon the rise of the float.

6. The combination with the condenser of an engine, the exhaust pipe thereof and a normally closed vacuum valve mounted in the exhaust pipe and controlling admission of atmospheric air thereto, of a cylinder, a piston therein operatively connected to the vacuum valve, a valve casing having an inlet port and an outlet port leading to the cylinder below the piston thereof, a valve in said valve casing normally preventing the passage of fluid through the valve casing to the cylinder but when raised permitting said passage, the chamber having a duct connected at its lower end to the lower portion of the condenser and at its upper end having a relatively smaller duct connected to the upper portion of the condenser, a float disposed in said chamber and having a diameter nearly equal to that of the chamber, said float being directly connected to the controlling valve whereby upon an upward movement of the float due to the accumulation of water within the condenser the controlling valve shall be shifted to open communication with a source of fluid and the cylinder to thereby cause the lifting of the vacuum valve, and means causing the return of the vacuum valve to its seat upon the descent of said float.

7. In a mechanism of the character described, a vacuum valve, a cylinder disposed above the vacuum valve and having therein a piston, the cylinder being connected to a source of water, a yoke connected at its lower end to the vacuum valve and extending upward around the cylinder, a piston rod extending from the piston and connected at its upper end to said yoke, and float operated means for controlling the passage of water into said cylinder.

In testimony whereof I hereunto affix my signature.

WALDO A. HOWLAND.
